UNITED STATES PATENT OFFICE.

GEORGE ALBERT LEY, OF CHICAGO, ILLINOIS.

FLASH-LIGHT IGNITER.

1,332,048.

Specification of Letters Patent. Patented Feb. 24, 1920.

Application filed November 2, 1917. Serial No. 199,942.

To all whom it may concern:

Be it known that I, GEORGE ALBERT LEY, a citizen of the United States of America, residing at Chicago, in the county of Cook 5 and State of Illinois, have invented new and useful Improvements in Flash-Light Igniters, of which the following is a specification.

The invention has general reference to flash light attachments to be used in conjunction with cameras.

Its principal object is to provide a device of this kind which may be connected with the shutter operating mechanism of a camera so that flash light powder may be ignited and the camera shutter operated simultaneously with the ignition of the powder.

A further object of the invention is to provide a flash pan having a spring operated hammer mounted on its outer face, the inner 20 face of the pan being provided with an anvil adapted to receive a cap against which the hammer may impact to ignite powder contained in the pan. The hammer is held normally away from the cap and to be released 25 by a trip member which is actuated by the shutter operating bulb.

A further object of the invention is to provide means connected with the device whereby it may be appropriately attached to a 30 convenient support.

A still further object is to provide a housing on the back of the flash pan for inclosing the hammer and its attendant operating mechanism, the anvil and cap support being 35 on the inside of the pan and the wall of the latter having formed therein an appropriate aperture through which the hammer may project to impact on the cap.

A still further object of the invention is 40 to provide an adjusting device connected with the hammer trip, so that the latter may be regulated for simultaneous operation with the camera shutter.

A still further object is to provide means 45 for locking the hammer away from the anvil, so that it may not be inadvertently operated.

A still further object is to provide a device 50 of this kind which is simple in construction, durable and effective in operation and inexpensive to manufacture.

Still further and other objects are made apparent as the detail description of the device progresses.

The drawings illustrate and the specification 55 describes a particular embodiment of

the invention, but to this embodiment the invention is not to be restricted. Continued practical use may make manifest certain desirable changes or alterations and the right is claimed to make any such changes or 60 alterations, in so far as they may be comprehended in spirit by the subjoined claims.

The same numerals of reference designate the same parts throughout the several figures of the drawings, wherein:

Fig. 1 is a perspective view of the improved flash pan and ignition apparatus.

Fig. 2 is a view in side elevation of the invention, the housing for the hammer and its attendant parts being shown in section.

Fig. 3 is a section on the line 3—3 of Fig. 2.

Fig. 4 is a section on the line 4—4 of Fig. 2.

Fig. 5 is a detail elevation of the anvil 75 and cap support.

Fig. 6 is a plan view of the structure of Fig. 5, the wall of the flash pan being shown in section.

Fig. 7 is a perspective view of the supporting member for the hammer.

Fig. 8 is a perspective view of one of the trip supports.

Fig. 9 is a perspective view of the hammer.

Fig. 10 is a perspective view of the trip lever.

Fig. 11 is a perspective view of the trip-lever tension-adjusting screw.

Fig. 12 is a perspective view of the trip.

Fig. 13 is a perspective view of the hammer operating spring.

Fig. 14 is a perspective view of the hammer keeper.

Referring to the drawings, the invention 95 is shown as comprising the flash pan A and the ignition mechanism B. The flash pan comprises a quadrangular plate 1 which is adapted to stand normally vertical and which is provided at the bottom edge with 100 a right angularly disposed web 2 which terminates in flange 3 turned up into a plane parallel with the plate 1, the web, the flange and the plate constituting a channel adapted to receive flash light powder. Substantially 105 at its longitudinal center and at a specified distance from the web 2, the plate 1 is provided with an aperture 4 and on the inner face of the plate there is suitably attached a U-shaped member 5 which carries an anvil 6 110

medially disposed between its legs and positioned concentric with the aperture 4. Between this anvil 6 and the adjacent wall of the plate 1, the ignition cap 7 is designed to be held, the cap being inserted between the plate and the anvil and being held in place frictionally, so that it may be set off by means yet to be described, this means impacting with the cap after passing through 10 the aperture 4.

On the outer face of the plate 1 and at a specified distance above the aperture 4, there is attached the hammer support 8 which is secured to the plate by rivets or other suitable means. This hammer support is provided with two outwardly projecting ears 9 between which the upper end of the hammer 10 is carried, this upper end being provided with a stud 11 which is rigidly secured in 20 the hammer and which is journaled in holes 12 formed in the ears 9. The hammer is provided with a poll 13 in registration with the aperture 4 in the plate 1, this poll passing into and out of the aperture on the 25 movement of the hammer on its pivotal connection with the support 8. The hammer 10 is provided with a projecting end 14 which extends below the plane of the web 2 of the flash pan and it is further provided with a 30 transverse pin 15 positioned in the vicinity of the poll.

To hold the poll 13 away from the anvil 6, there is provided a trip member comprising two plates 16 which are interconnected near either end by pins 17 and 18, the two pins being rigidly attached in the plates and holding them appropriately spaced, so that the trip member may be placed in surrounding relation to the hammer just above the 40 poll 13 thereof. The pin 18 is of sufficient length to extend laterally from the outside of either plate 16 and these lateral extensions are journaled in holes 19 formed near the upper end of ears 20 which are integral parts 45 of the supports 21 appropriately secured to the plate 1 by rivets or any other suitable means. The supports 21 are positioned one on either side of the hammer 10, so that they may hold the trip member in the surrounding 50 relation to the hammer previously referred to.

The supports 21 are further provided with outwardly projecting ears 22 which lie in a plane at right angles to the planes of the ears 20. Each ear 22 is provided with a hole 23 in which there is fixed the end of one leg 24 of the U-shaped spring 25. The U-shaped spring 25 is formed with coils 26 medially positioned in its legs whose free 60 ends 24 are turned back on those portions of the legs which connect with the transverse portion of the spring. The spring being attached by having the free ends of its legs 24 fixed in the holes 23 of the ears 22, the transverse portion of the spring engages the ham-

mer on that side opposite the poll 13, the spring thus tending to force the poll into contact with the anvil.

Each of the plates 16 is provided with a notch 27 and these two notches are engaged by the transverse pin 15 of the hammer to hold the hammer poll 13 away from the anvil against the pressure of the U-shaped spring 25.

To provide means for moving the trip out 75 of engagement with the hammer, a trip lever 28 is provided, this lever being pivotally connected to the plate 1 on one side of the hammer by means of an appropriate bolt 29. The trip lever passes underneath 80 the hammer and terminates in a portion 30 which is contacted with by the free end of the air piston 31, the latter being slidably mounted in a small air pump 32 which is appropriately attached to the plate 1 by means 85 of appropriate rivets which pass through the ears 33 formed on opposite sides of the pump. The end of the pump is provided with a nipple 34 arranged for the convenient attachment of the hose 35 whose other end 90 connects with a bulb 36.

A T 37 is interposed in the hose 35 and to this T a hose 38 is attached which is designed to connect with the shutter operating mechanism of a camera.

The trip lever 28 is provided with a link 39 which is pivotally connected at one end to the lever 28 and at the other end to the pin 17 of the trip, the pivotal connections at the two ends of the link being arranged for 100 movement in planes at right angles to each other. It will be observed that raising that end of the trip lever 28 which is engaged by the piston 31 will operate to move the trip on its pivotal connections with the supports 105 21, thus withdrawing the notches 27 from engagement with the pin 15 of the hammer, when the spring 25 will operate to drive the hammer and its poll 13 toward the anvil 6. The trip lever 28, however, is normally precluded from this upward movement by a spring 40 whose one end engages a hole 41 formed in the lever and whose other end 110 engages an eye 42 formed at one end of an adjusting screw 43.

The hammer and all its attendant mechanism are appropriately inclosed within a housing 44 which is provided with a flange 46 through which bolts 45 pass. The latter also pass through the plate 1 and effect the 120 attachment of the housing to the plate. The bottom portion of the housing extends below the web 2 thus providing a flange 47 through which bolts 48 pass and effect the attachment of the flange 47 to the web. The bottom of 125 the housing 44 is provided with suitable openings through which the extension 14 of the hammer, the lower end of the adjusting screw 43 and the nipple 34 may pass. The adjusting screw 43 is flattened longitudinally 130

on one side and the hole in the housing 44 through which the screw passes is of a contour conforming to the cross-sectional outline of the screw as defined by the flat formed thereon. The screw 43 is thus precluded from angular movement but exterior to the housing it receives a knurled nut 49, which abuts the bottom of the housing 44 and whose turning operates to increase or relieve the tension on the spring 40, depending on whether the screw is turned left handedly or right handedly.

On the bottom of the housing 44 and positioned adjacent the extension 14 of the hammer, there is a keeper or lock 50 whose one end is pivotally attached to the flange 47 and whose other end extending beyond the outer wall of the housing is upturned and then turned back on itself, thus providing a hand piece 51 by means of which the keeper may be moved on its pivotal connection. This pivotal movement of the keeper, however, is not great, its arc of movement being limited by the hand piece 51 whose either side engages the outer face of the housing after a prescribed angular movement of the keeper. The hand piece 51 is of less width than the main portion of the keeper, thus providing a shoulder 52 on top of which the extension 14 of the hammer may engage, the engagement of the extension with this shoulder precluding movement of the hammer, irrespective of whether the trip is operated or not.

A hook member 53 is appropriately attached to the housing 44 adjacent the top, this hook member providing means for suitably supporting the device as a whole on the tripod of the camera or on some other stand adjacent thereto.

In the operation of the device, the hose 38 is attached to the shutter operating mechanism of a camera with which it is desired to take a flash light picture. The invention is then attached to an appropriate support by means of its hook member 53 and flash light powder is deposited in the channel formed by the web 2, the flange 3 and the plate 1. The cap for igniting the flash light powder is inserted between the anvil 6 and the plate 1 where it is frictionally held in place. The poll 13 of the hammer is held away from the cap by the engagement of the pin 15 with the notches 27 of the trip, there being a tendency on the part of the trip to effect this engagement because of the force exerted by the spring 40 on the trip lever 28 whose link 39 engages the pin 17 of the trip. When the hose 35 is attached to the nipple 34, the device is then in condition for use. Pressure exerted on the bulb 36 serves to drive air through the hose 38 and through the hose 35 as well, the air in the former operating the shutter mechanism of the camera and the air in the latter forcing the piston 31 upward

and raising the free end of the lever 28 against the pressure of the spring 40. This raising of the free end of the lever 28 operates to raise that end of the trip carrying the pin 17, thus withdrawing the notches 27 from engagement with the pin 15, whereupon the spring 25 operates to drive the hammer toward the plate 1, the poll 13 of the hammer passing through the apertures 4 and impacting on the cap, thus exploding the latter and causing it to ignite the flash light powder contained in the flash pan.

The nut 49 is provided for the purpose of so regulating the tension of the spring 40 that the trip lever 28 will be assured of withdrawing the trip at the time of the operation of the shutter. Thus the ignition apparatus may be always adjusted to operate simultaneously with the shutter operating mechanism of any camera with which the invention is used.

To insure against inadvertent operation of the ignition apparatus, the keeper 50 is provided. This keeper may be thrown into or out of engagement with the hammer. When the extension 14 of the hammer rests upon the shoulder 52 of the keeper, the hammer is prevented from effecting the ignition of any flash light powder that may be contained in the flash pan even though the trip lever may be operated, and there be a cap on the anvil.

It will be observed that the device, having once been operated, may be restored to its normal set position by simply moving the hammer by means of that portion of its extension 14 which protrudes from the housing 44. When the hammer is withdrawn away from the anvil after having once been impacted with the latter, the spring 40 operates to return the lever 28 to its normal position and in so doing effects the engagement of the notches 27 of the trip with the pin 15 of the hammer. Thus the simple movement of the hammer by hand to withdraw the poll from the anvil, serves to reset the whole mechanism with the exception of providing a new cap and new powder for a second flash light.

By reason of the hammer 10, when set, being supported on both sides by the trip, the trip is released by a much lighter pressure on the bulb than would be necessary if the trip supported the hammer on one side only.

The invention having been described, what is claimed as new and useful is:

1. The combination with a flash pan having a receptacle for flashlight powder, of a cap supporting means mounted on the pan adjacent the said receptacle, a hammer pivotally mounted on the opposite face of the flash pan, the hammer being formed with a poll, the flash pan formed with an aperture through which the said poll may reach the

cap-supporting means, a pin inserted transversely through the hammer, an open trip surrounding the hammer and having notches for engagement with said pin, means for springingly supporting the trip on the flash pan, resilient means tending to force the hammer poll toward the cap-supporting means, and means for operating the trip to withdraw the notches from the pin to permit the hammer being driven toward the cap-supporting means.

2. The combination with a flash pan having a receptacle for flashlight powder, of means for supporting an ignition cap therefore, a hammer pivotally mounted on the flash pan on the side opposite said means, the flash pan having an aperture through which the said hammer may reach said means, a transversely disposed pin carried by the hammer, an open trip surrounding the hammer and formed with notches for engagement with said pin, means for pivotally supporting said trip on the flash pan, a trip lever pivotally mounted on the flash pan, a link connection between said lever and said trip, and means for moving the lever on its pivotal connection to swing the trip to disengage its notches from the aforesaid pin for the useful purpose specified.

3. The combination with a flash pan having a receptacle for flashlight powder, of means for supporting an ignition cap therefore, a hammer pivotally mounted on the flash pan on the side opposite said means, the flash pan having an aperture through which the said hammer may reach said means, a transversely disposed pin carried by the hammer, an open trip surrounding the hammer and formed with notches for engagement with said pin, means for pivotally supporting said trip on the flash pan, a trip lever pivotally mounted on the flash pan, a link connection between said lever and said trip, a spring tensioned between the lever and the flash pan whereby the notches on the trip are kept in engagement with the said pin, a spring tending to force the hammer toward the cap-supporting means, and means for shifting the lever on its pivotal connection against the tension of its spring, whereby the notches of the trip are withdrawn from the pin of the hammer for the useful purpose specified.

GEORGE ALBERT LEY.
